CLAIM

The ornamental design for a cable insulation stripper, as shown and described.

DESCRIPTION

FIG. 1 is a front elevational view of the cable insulation stripper showing my new design;

FIG. 2 is a rear elevational view thereof;

FIG. 3 is a right side elevational view thereof, the left side being a mirror image;

FIG. 4 is a perspective view thereof, shown on a reduced scale.

FIG. 1

FIG. 2

FIG. 3

FIG. 4
